UNITED STATES PATENT OFFICE.

LOUIE A. SHERMAN, OF KANSAS CITY, MISSOURI, ASSIGNOR OF ONE-HALF
TO HARRY E. SHERMAN, OF KANSAS CITY, MISSOURI.

TARGET-TRAP.

No. 827,945.

Specification of Letters Patent.

Patented Aug. 7, 1906.

Application filed May 22, 1902. Serial No. 108,463.

To all whom it may concern:

Be it known that I, LOUIE A. SHERMAN, a citizen of the United States, residing at Kansas City, in the county of Jackson and State of Missouri, have invented a new and useful Improvement in Target-Traps, of which the following is a specification.

This invention relates to target-traps.

The object of the invention is to provide a construction of target-trap which is simple and efficient.

A further object of the invention is to provide a target-trap which may be continuously operated.

15 A further object of the invention is to provide a construction of target-trap wherein the throwing movement of the trap-arm is utilized in aiding the resetting of the arm for the next throw.

20 A further object of the invention is to provide a magazine target-trap of simple and efficient construction and arrangement.

Other objects of the invention will appear more fully hereinafter.

25 The invention consists substantially in the construction, combination, location, and arrangement of parts, all as will be more fully hereinafter set forth, as shown in the accompanying drawings, and finally pointed out in

30 the appended claims.

Referring to the accompanying drawings and to the various views and reference-signs appearing thereon, Figure 1 is a view in side elevation of an apparatus embodying the principles of my invention, a portion of the carrier-frame and the mechanism carried thereby being broken off. Fig. 2 is a sectional detail view on the line 2 2, Fig. 1, looking in the direction of the arrow. Fig. 3 is a

35 view in side elevation of the carrier-frame and its associated parts, the supporting-standard for said frame and the driving-shaft being broken off. Fig. 4 is a broken detail view in perspective of the follower which

40 holds the targets in the magazine. Fig. 5 is a top-plan view of the carrier-frame and carrier-arm and of the mechanism for actuating the latter. Fig. 6 is a sectional view on the line 6 6, Fig. 3, looking in the direction of the arrows. Fig. 7 is a broken detail view in section on the line 7 7, Fig. 1, looking in the direction of the arrows. Fig. 8 is a broken detail view, in longitudinal section, of the carrier-arm-operating shaft, the section being on the

line 8 8, Fig. 1. Fig. 9 is a transverse section of the same on the line 9 9, Fig. 8. Fig. 10 is a detail view, in rear elevation, parts in section, of the driving mechanism. Fig. 11 is a sectional view on the line 11 11, Fig. 6, looking in the direction of the arrows. Fig. 12 is a transverse section on the line 12 12, Fig. 11, looking in the direction of the arrows. Fig. 13 is a view in top plan of a magazine employed in connection with a target-trap and embodying the principles of my invention. Fig. 14 is a view similar to Fig. 13, showing a displaced position of the parts. Fig. 15 is a view in side elevation of the construction shown in Figs. 13 and 14.

The same part is designated by the same reference-sign wherever it occurs throughout the several views.

Referring to the accompanying drawings, reference-signs A, B, and C designate brackets or standards constituting the framework of the machine and upon which the various operating parts are mounted. Upon standard or bracket C is mounted a seat D, which may be of any suitable or convenient construction—as, for instance, an ordinary bicycle-seat—affording a convenient support or rest for the operator. Also supported upon bracket or standard C is a table or platform E, arranged in convenient position to support the targets in quantity, enabling the operator to supply the same therefrom to the projecting apparatus or the magazine, as may be desired. This table or platform also affords a convenient support or rest for the arms or hands of the operator when seated upon seat D. In suitable bearings formed in the bracket or standard B is a vertical shaft F, upon which is mounted a gear-wheel G and a fly or balance wheel H, the function of the latter element being to maintain a steadiness in the operation of the apparatus. Transversely journaled in the bracket or standard B is a short crank-shaft J, carrying the crank-arms K at the ends thereof in a manner similar to the crank-shaft and crank-arms of a bicycle, and upon which crank-arms are mounted or carried pedals L, if desired, the arrangement being such as to enable an operator seated upon the seat D to impart rotation to crank-shaft J with his feet through the pedals L and crank-arms K. Mounted upon crank-shaft J are bevel-gears M, N, the latter of which intermeshes with bevel-gear

G on shaft F, thereby imparting rotation to the latter. The bevel-gear M meshes with and drives a bevel-gear O, mounted upon a short shaft P, journaled in bracket or stand-
ard B.

5 Q designates a shaft suitably journaled in the framework and driven from shaft P or other convenient rotating part of the operating mechanism in any suitable or convenient manner—as, for instance, through the intermeshing spur-gears R S.

T designates a standard suitably stepped or journaled in frame-bracket A for axial rotation or oscillation. Connected to stand-
ard T is an arm V, arranged to be received freely through a slot or opening W in a head A', pivotally mounted upon a rocking arm B'. This rocking arm B' is pivotally mounted intermediate its ends upon a stud or other convenient bearing on a fixed part of the framework and at its lower end is provided with an elongated slot C', in which operates a crank-pin D', connected to and operated from shaft Q.

15 25 From the foregoing description it will be seen that when rotation is imparted to shaft Q the crank-arm D' connected thereto, operating in elongated slot C', effects an oscillation in a vertical plane of arm B' about its supporting stud, or pin, and by reason of such rocking motion and the engagement in the slot in the swivel-head A' of arm V an axial 30 35 rocking movement is imparted to standard T in its journal-bearing in the framework, the swiveling of head A' upon arm V permitting such oscillatory movement of standard T. If desired and in order to reduce friction, the swivel-head may comprise anti friction-rollers, as clearly shown in Figs. 2 and 7, between which the arm V operates.

40 E' designates a supplemental frame upon which the carrier and its operating mechanism are mounted, as will presently be more fully explained. This frame E' is pivotally supported upon standard T, as at F', and consequently is vibrated or oscillated when said supporting-standard T is rocked, as above described, about the vertical axis of said supporting-standard. The angular position of frame E' with reference to its supporting-standard may be adjusted or varied to give the desired angle to said carrier-arm in any suitable or convenient manner. For instance, in the form shown a segment-arm G' 45 50 55 is pivotally connected at one end to frame E' and may be adjustably secured to the standard T at any desired point to vary the inclination of said frame E' and of the carrier-arm with reference to standard T.

60 65 H' designates the carrier upon which the targets are placed preparatory to being projected. This carrier is mounted upon the outer or free end of an arm J', which I will designate the "carrier-arm," said arm being mounted at its other end upon the axially-ro-

tating part K' of a double-crank shaft suitably journaled in bearings formed in auxiliary or carrier frame E'. Pivotally connected or supported upon carrier-arm J' is a pawl L', arranged to coöperate with a segment-
70

75 rack M', suitably supported upon frame E' in an encircling relation with respect to the part K'. This double crank is composed of the parts K' N', which rotate axially and are in longitudinal alinement with each other, the crank-arms O' P', and the connecting-pin Q'. To the pin Q' is connected one end of a stout retractile spring R', the other end of said spring being connected to a bolt S', arranged to extend through an opening in frame E', a spring T' being interposed between a nut V', mounted on the threaded end of bolt S', and frame E'. The spring R' 80

85 may be otherwise suitably connected to the frame E', if desired. Detachable stop devices A² B² may be respectively mounted upon the carrier-arm J' and frame E' to form a stop or lock for the carrier-arm J' to hold the same in position preparatory to projecting a target. Many specifically different 90

95 constructions of stop devices may be employed for this purpose. That form shown in my application for patent, Serial No. 43,488, filed January 16, 1901, Patent No. 696,763, April 1, 1902, I have found to be efficient for 95 this purpose.

The arrangement of the spring R' and its connection to the cross-pin Q' and crank-arms O' P' is such that when carrier-arm J' is in position, as shown in Fig. 5—that is, the position thereof preparatory to projecting a target—said arm being held in such position by the detachable locking devices A² B², the line of pull exerted by spring R' has passed the dead-center of crank-arm P'. This relative position of the parts will be made clear by reference to Fig. 5, wherein the geometric center of the dotted circle (designated by reference-sign Q') is the point of application of the tension of spring R', tending to impart a rotation or rotative movement to crank-arm P', and the small dotted circle (indicated by reference-sign C²) designates the point of attachment of the other end of spring R' to frame E', and a line joining the points C² and Q' in Fig. 5 will designate the line of pull exerted by the spring R' upon crank-arms O' P', and it will be observed that this line is to one side of the center of rotation of the part K' of the double-crank shaft, and consequently when arm J' is in the position shown in Fig. 5 preparatory to being released with a target the tension of spring R' is applied in a manner to impart a rotative tendency to the double-crank shaft, upon the part K' of which carrier-arm J' is mounted.

100 105 110 115 120 125 130 I will now describe the power-actuated mechanism for setting the arm J', particular reference being had to Figs. 3, 5; 6, 11, and 12, wherein D² designates a shaft suitably

journaled in bearings formed in carrier-frame E'. Upon this shaft is arranged a head E², carrying suitably-separated studs or pins F², arranged off center with respect to the axis of rotation of shaft D², said studs being received through an elongated slot or opening G², formed in a block H², so that when shaft D² is rotated a rotation is also imparted to block H²; but said block is capable of longitudinal movement upon the studs F², said studs forming a guide therefor and also forming a means for applying the rotative power to said block. Carried by block H² is a stud or projection J², operating in a cam-groove K², formed in a plate or disk L², suitably mounted upon bracket E'. This cam-track K² is so relatively arranged that when rotation is imparted to shaft D² such rotation is transmitted to block H², to which a longitudinal reciprocation or movement is imparted by the pin or stud J², traveling in cam-slot K². If desired, the disk or plate L² may be adjusted upon frame E', so as to regulate or vary the point of greatest longitudinal projection of block H². This adjustment may be effected by means of securing-bolts M², operating through circular slots N². (See Fig. 12.) Pivotedly mounted upon the end of block H² is a projecting toe O², having a flat front or engaging surface and a beveled rear surface, (indicated at P², Fig. 6.) The toe O² is acted upon by a spring Q², which permits a slight yielding movement thereof relative to its supporting-block H². Connected to the part N' of the double-crank shaft is a crank-arm R², arranged to be engaged by the front or engaging side or face of toe O² when block H² is rotated and sufficiently projected by the cam-slot K², whereby rotary movement is imparted to said crank-arm R² and to the double-crank shaft. The part of crank-arm R² with which the pivoted toe O² engages is beveled on its forward side, as indicated at S², Fig. 3, and in dotted lines in Fig. 6, the function of which is, in cooperation with the rear beveled surface P² of toe O² and the yielding movement permitted said toe O² by spring Q², to enable the crank-arm R² to overtake and pass the toe O² without undue obstruction when said crank-arm R² is moved in the same rotative direction with but at a greater rate of speed than that of block H². The operation of this feature of the invention is as follows: Rotation is imparted to shaft D² and through it to block H². The cam-slot K² effects a longitudinal projection or extension of block H² to permit the pivoted toe O² to engage on its front flat or engaging surface with the rear edge of the engaging part of crank-arm R², thereby imparting rotation to said crank-arm and through it to the double-crank shaft, upon which is mounted the carrier-arm J', thus effecting a sweep or rotative swing of said carrier-arm. This rotary sweep or swing of said

carrier-arm continues about the axis of the part K' of the double crank until the line of tension of spring R' approaches a dead-center with respect to crank-arms O' P'. As this point is approached the cam-track K' gradually withdraws block H² and the toe O² thereof out of engaging relation with respect to the engaging part of crank-arm R², and by the time the connecting-pin Q' passes beyond this dead-center to enable the tension of spring R' to exert itself in imparting a rotative or swinging movement to carrier-arm J' the toe O² is entirely withdrawn from engaging relation with respect to crank-arm R² and the carrier-arm J' is held against the stop devices A² B² under the tension of spring R' or in the position of the parts indicated in Fig. 5. Thereafter shaft D² and block H² may continue their rotations and the projection of the latter without effecting an engagement of toe O² with crank-arm R² and without disturbing the position of the carrier-arm J', which remains ready to be released by the disengagement of the stop devices A² B² when said stop devices are actuated and to be given a rotary spring under the impetus imparted by the tension of spring R'. When the stop devices A² B² are released or disengaged, the spring R' quickly swings or rotates the double-cam shaft, thereby swinging arm J' about the axis of rotation of the part K' of said shaft, and hence projecting the target, which has been previously placed upon the carrier H'. The momentum thus imparted to carrier-arm J' acts upon said carrier-arm to rotate or swing the same in a single plane or in a circle, and the pawl L' thereon engaging in the rack-teeth M' serves to prevent a return movement in the opposite direction. Thus it will be seen that carrier H' describes a complete circle, the momentum imparted thereto when the carrier-arm J' is released from the stop devices A² B² aiding in effecting a complete circular swing of said arm. It will also be seen that the detachable clutch mechanism may be continuously operated, and in its swing carrier-arm J' or its actuating crank-arm R² may overtake and pass the pivoted toe O², the yielding movement of said toe permitting the free passage of said crank-arm past said toe. The continuous operation, however, of the clutch mechanism, which includes the toe, will eventually overtake the carrier-arm in its arrested position, said arrest being effected by the pawl L' and rack M', and the carrier-arm J' will again be forced or carried by the power mechanism in continuation of its swinging or rotary movement into initial position preparatory to projecting a target. It will also be seen that the construction is such that, if desired, the power mechanism for placing the carrier-arm in initial position preparatory to effecting a throw may be arrested and the carrier-arm placed in its ini-

tial preparatory position by hand. The adjustment shown in Fig. 12 for cam plate or disk L^2 serves to enable the exact point at which the toe O^2 may be disengaged from 5 crank-arm R^2 to be adjusted. Rotation may be imparted to shaft D^2 from the drive-shaft A^3 through the intermeshing bevel-gears B^3 .

As above explained, the position of carrier-frame E' upon its supporting-standard T 10 may be adjusted to vary the inclination at which the carrier-arm operates. It is also described how a rotary oscillation is imparted to supporting-standard T . It is necessary, therefore, in transmitting motion from 15 the power mechanism to the carrier-arm-actuating mechanism to provide for this rotary oscillation and inclination adjustment of the carrier-frame E' . I have shown a simple and efficient construction for accomplishing 20 this result, wherein shaft-sections $C^3 D^3$ are respectively connected by gimbal-joints $F^3 G^3$ to shafts P and A^3 . The opposite ends of 25 the shaft-sections $C^3 D^3$ are arranged to slide longitudinally through a hollow sleeve H^3 . I have shown a construction of coupling connection between the sections $C^3 D^3$, which is 30 simple and which I have found exceedingly efficient, wherein at its ends sleeve H^3 is provided with longitudinal channels or grooves 35 J^3 , coöperating with similar grooves or channels K^3 , formed in the shaft-sections $C^3 D^3$, thereby forming seats or ways in which may be arranged antifriction - balls L^3 , the balls being retained in the pockets formed by the 40 coöperating grooves $J^3 K^3$ by means of pins M^3 . By this construction of shaft-coupling from the power mechanism to the carrier-arm-actuating mechanism I am enabled with the least degree of friction to secure the 45 rotary oscillations of the carrier-frame-supporting standard T and the vertical inclination adjustment of the carrier-frame upon its supporting-standard.

Any specific form of carrier may be employed in connection with my invention. I 45 have shown in the drawings a simple and efficient form of carrier which I have found suitable in the practical operation of my invention, and wherein the carrier (designated generally by reference-sign H' in the drawings) is rigidly bolted or secured to the free end of carrier-arm J' , and which comprises a platform or support N^2 , upon which is received the target. The carrier is provided with a 50 curved track O^3 of the usual construction, against which the edge of the target rolls while being projected. A target-clamping lug P^3 is mounted upon an arm Q^3 , pivotally carried upon the opposite side of supporting-frame N^2 from the curved guiding-track O^3 , a tension-spring R^3 being connected to said arm Q^3 to hold the clamping lug or finger P^3 in proper position. In the operation of the carrier a target is placed by hand or from a 55 magazine or otherwise, as may be convenient,

upon the supporting part N^2 of the carrier. This work may be conveniently performed by the operator of the machine seated upon the seat D , the operator successively placing the targets upon the carrier by dropping the 70 same upon the outer surface of the part N^2 thereof or the targets may be deposited upon the carrier from the magazine, presently to be described. No clamping of the target upon the carrier is necessary, the initial 75 swinging movement of the carrier-arm when released serving to cause the target through its own inertia to be moved in a direction for the peripheral edge thereof to be engaged in the track or guide O^3 and between such guide 80 and the clamping-finger P^3 , the target being finally discharged with a rotary or spinning movement when the carrier-arm reaches the proper position in its swinging or sweeping movement. Thus it will be seen that it is 85 not necessary to supply the targets to the center of rotation of the projecting arm, but they are placed upon the carrier at a point considerably off the center of rotation thereof or from a point to the rear of such center 90 of rotation with reference to the direction of projection of the target, the desired clamping of the target in the carrier being effected through the tension-spring R^3 .

I will now describe a construction of magazine which I have found efficient in the operation of an apparatus embodying the principles of my invention, particular reference being had to Figs. 3, 4, 13, 14, and 15, wherein A^4 designates an arm suitably supported 95 upon the carrier-frame E' and upon which is mounted a circular frame B^4 , having a central opening therethrough of sufficient dimensions to permit the targets to be dropped therethrough onto the carrier H' when the latter is brought into proper position with reference thereto, as shown in Fig. 3. Extending vertically from the base ring or plate B^4 are sections C^4 of side walls, forming a containing easing in which the targets may be 100 stacked the one upon the other. Pivotedly mounted, as at D^4 , upon the base-ring B^4 are the levers $E^4 F^4$, said levers being curved or bent into somewhat encircling relation with respect to the central opening through the 105 base-ring B^4 . The front or free ends of levers $E^4 F^4$ are yieldingly drawn toward each other by means of a tension-spring G^4 , adjustably connected at its ends, respectively, to the levers or arms $E^4 F^4$. A stud H^4 is 110 pivotally journaled in the base-ring B^4 and carries a cam J^4 , arranged to operate against the abutting or adjacent ends of levers $E^4 F^4$, so that when stud H^4 is rocked said levers $E^4 F^4$ will be engaged by the cam J^4 and 115 swung about their pivots D^4 and against the action of the spring G^4 , the tension of which is normally exerted to maintain the free ends of said levers drawn toward each other. In 120 Fig. 13 the cam J^4 is shown in the position 125 130

thereof which permits the free ends of levers $E^4 F^4$ to be drawn together or into close relation with each other, while in Fig. 14 the parts are shown in the position thereof when said levers $E^4 F^4$ are spread apart by the operation of cam J^4 . A stop K^4 serves to limit the extent of rocking movement of cam J^4 . The stud H^4 , by means of which cam J^4 is rocked, may be provided with an arm L^4 , by which said pin or stud H^4 is rocked. The pin or stud H^4 may be held in the initial position thereof, as shown in Fig. 13, in any suitable manner—as, for instance, by means of a retractile spring M^4 , (see Figs. 3 and 15)—so that when said pin is rocked to cause the free ends of the arms or levers $E^4 F^4$ to be spread apart said rocking movement is opposed not only by the tension of spring G^4 , which operates to draw the free ends of said arms or levers together or toward each other, but also such rocking movement of pin H^4 is opposed by its retractile M^4 , the tension of which is constantly exerted to maintain cam J^4 in the position thereof as shown in Fig. 13 and against its limiting-stop K^4 . Suitably connected to each of the arms or levers $E^4 F^4$ is a retaining plate or section N^4 , which when the arms or levers $E^4 F^4$ are drawn together or toward each other, as shown in Fig. 13, project slightly into the central space or opening through the base-ring B^4 , such projection being sufficient to permit said ring sections or plates N^4 to form a ledge or support on opposite sides of said opening upon which the lowermost target of the stack or pile contained in the magazine rests at its edges. When, however, the arms or levers $E^4 F^4$ are spread apart by the manipulation of cam J^4 and from the position thereof as shown in Fig. 13 to the position shown in Fig. 14, the supporting-plate sections N^4 being connected to said arms or levers are withdrawn from supporting relation with respect to the lowermost one of the stack or pile of targets contained in the magazine, thereby releasing said lowermost target and permitting the same to fall through the central opening of the base-ring B^4 . It is important, however, to sustain the remaining targets contained in the magazine so that only one target will be released when the levers $E^4 F^4$ are spread apart. To accomplish this result, I provide auxiliary levers $O^4 P^4$, suitably pivoted, as at Q^4 , upon the base-ring B^4 and carrying at their free ends clamping-jaws R^4 . If desired, these clamping-jaws may be faced with felt, rubber, or other suitable material, as indicated at S^4 . The auxiliary levers $O^4 P^4$ are mounted on opposite sides of the opening through the base-ring B^4 and through any suitable connections are projected into the space of the opening through the base-ring when levers $E^4 F^4$ are separated and are withdrawn from projection into such space when said levers $E^4 F^4$ are drawn together. Thus in the position

of the parts shown in Fig. 13 the clamping-jaws R^4 are withdrawn, and in the position shown in Fig. 14 these clamping-jaws are projected into the space of the opening through the base-ring B^4 . Thus it will be seen that the clamping-jaws R^4 are projected and withdrawn alternately with respect to the projections and withdrawals of supporting ring-sections C^4 . Therefore when the supporting ring-sections C^4 are projected into the space of the opening through the base-ring to form a supporting-ledge for the edges of the lowermost target contained in the magazine the clamping-jaws R^4 are withdrawn, thereby permitting the entire stack of targets contained in the magazine to rest upon the support afforded the lowermost target by the ring-sections N^4 . When, however, the ring-sections N^4 are withdrawn to permit the lowermost target to be released, the clamping-jaws R^4 are projected into clamping relation with respect to the next target, thereby supporting the stack or pile in the magazine, while the lowermost one is permitted to drop through the opening in the base-ring and onto the carrier. The desired alternating movement of clamping-jaws R^4 with respect to the movement of the supporting ring-sections or flanges N^4 may be secured in many different ways. I have shown a simple arrangement wherein bell-crank levers $A^5 B^5$ are pivotally mounted at their angles upon the base plate or ring B^4 and are provided with elongated slots $C^5 D^5$ at their ends. In the slots C^5 at one end of said bell-crank levers $A^5 B^5$ operate pins or studs E^5 , respectively carried by levers $E^4 F^4$, and in the slots D^5 at the opposite ends of said bell-crank levers $A^5 B^5$ operate pins or studs F^5 , respectively carried by the auxiliary levers $O^4 P^4$. Therefore when levers $E^4 F^4$ are drawn together the bell-crank levers $A^5 B^5$ are rocked in a direction to swing the auxiliary levers $O^4 P^4$ outwardly, thereby withdrawing the clamping-jaws R^4 , and when said arms or levers $E^4 F^4$ are separated or spread apart the bell-crank levers $A^5 B^5$ are rocked in a direction to swing auxiliary levers $O^4 P^4$ toward each other to project the clamping-jaws R^4 into the space of the opening through the base-ring B^4 , as will be clearly understood. It is desirable to constantly press the stack or pile of targets contained in the magazine downwardly toward the discharge-opening through the base-ring B^4 and to prevent displacement of the targets on account of vibrations due to the release of the carrier-arm. This result may be accomplished in many specifically different ways. I have shown a simple manner of accomplishing the desired object, wherein I employ a follower-plate G^5 , having arms H^5 terminating in a downwardly-turned flange or end J^5 . This flange is provided with a slot or opening K^5 therein,

(see Fig. 4,) which slot or opening extends into the downwardly-turned portion J^5 . Slots K^5 in the arms H^4 operate over vertical rods L^5 , suitably supported upon the base-ring B^4 , and from the foregoing description, taken in connection with the accompanying drawings, it will be seen that the follower-plate G^5 is permitted to descend upon the rods L^5 as guides as the targets are successively delivered from the magazine, thereby imposing upon the stack or pile of targets a downward pressure which aids gravity in effecting a feed of the targets from the magazine. It will also be seen from the peculiar construction of the guide-arms H^5 with the downturned slotted flange at their ends that while said follower-plate is permitted an up-and-down sliding movement upon guide-rods L^5 the rocking or tilting movement of the follower is prevented. Therefore the follower-plate G^5 serves as a lock to prevent displacement of the targets under the vibration imparted by the release of the carrier-arm. In order to enable the follower to be removed to permit of the insertion of additional targets in the magazine, the upper ends of guide-rods L^5 are bent outwardly, as indicated at M^5 , thereby permitting the follower-plate G^5 to be slid down said inclined ends M^5 of the guide-rods and out of the way of interference with the insertion of targets into the magazine, as clearly shown in Fig. 3. To permit the follower to be raised when desired, it is provided with a handle N^5 .

35 When the magazine is employed, it is desirable to provide means whereby the target holding and releasing devices of the magazine may be actuated automatically whenever the carrier-arm is brought into proper relation to receive a target. This result may be accomplished in any simple or convenient manner. I have shown an arrangement wherein I mount a rod or stem O^5 upon the carrier-arm in position to engage the arm L^4 , which is connected to the cam stud or pin H^4 , (see Figs. 3 and 5,) so that whenever the carrier-arm is brought into position to receive a target from the magazine the arm L^4 is rocked by the engagement therewith of the pin or stud O^5 , thereby effecting a separation of the levers or arms E^4 F^4 , and a target is released and is permitted to drop into position upon the carrier, and when the carrier-arm is released or thrown the pin or projection O^5 passes on by the arm L^4 , thereby permitting the return of said arm under the influence of its retractile M^4 and the tension of spring G^4 to its initial position, as shown in Fig. 13.

60 From the foregoing description it will be observed that the carrier H' instead of being pivotally connected to the carrier-arm J' is rigidly connected thereto. I do not desire, however, to be limited to a rigid connection of the carrier to the carrier-arm. It will also be seen that the carrier-arm describes a com-

plete circle of rotation instead of being swung from retracted position to forward position and then returned or rocked or swung back in the opposite direction. In this manner, therefore, I make use of the impetus produced by the throw of the carrier-arm in aiding the return of the carrier through the remaining portion of its complete circular rotation or swing, the extent of swinging motion of the arm under the impetus of its projecting spring R' being retained by the pawl L' , operating over the rack-teeth M' and the power mechanism operated by the driving crank-shaft J overtaking the position of the carrier-arm and completing its rotative or swinging movement back to initial position. It will also be seen that the targets are fed to the carrier either by dropping the same directly upon the carrier from the magazine, or in case the magazine is not employed they are deposited upon the upper surface of the carrier either by dropping the same by hand thereon or else by sliding the same laterally into place thereon when the carrier is in the position thereof preparatory to being discharged or as it approaches that position, and hence the targets are deposited upon the carrier from a point off the center of rotation of the carrier-arm. It will also be seen that I provide a detachable coupling by which the carrier-arm is returned to its initial position preparatory to discharging a target by a detachable clutching mechanism which co-operates with the spring, under the tension of which the carrier-arm is thrown when released. It will also be observed that I provide a construction wherein a swinging or oscillating movement is imparted to the carrier-frame during the continuous operation of the apparatus, which is a desirable feature in target-traps in order to prevent the throwing of the targets constantly in the same direction, as the marksman is not apprised in advance of the particular direction in which the target is to be thrown, and in the accomplishment of this result I provide a construction of power-transmitting shaft embodying a ball-bearing feather which permits the swinging or oscillating movement of the carrier-frame. It will also be observed that I provide an exceedingly simple and efficient construction of detachable clutch mechanism by which the carrier-arm is positively and by power-driven mechanism returned to position to be actuated in effecting a discharge of the target and which detachable clutch mechanism includes a yielding toe or extension which permits the carrier-arm to readily and freely pass by without undue obstruction when thrown. It will also be observed that I employ a magazine of exceedingly simple and efficient construction for automatically depositing the targets singly upon the carrier.

While I have described specific constructions of the various features of my invention

and the best form in which I have embodied the same in practical operating mechanisms, I desire it to be understood that my invention is not to be limited or restricted to such specific constructions as shown and described; but many variations and changes therefrom and in the details of construction thereof would readily occur to persons skilled in the art and still fall within the spirit and scope of my invention; but,

Having now set forth the object and nature of my invention and a construction embodying the principles thereof, what I claim as new and useful and of my own invention, and desire to secure by Letters Patent, is—

1. In a target-trap, a carrier-arm mounted for rotary swinging movement, a carrier mounted thereon, means for imparting a throw to said arm, and continuously-operating power mechanism for completing said swinging movement to return the arm to initial position, as and for the purpose set forth.

2. In a target-trap, a carrier-frame, a rotatable shaft mounted therein, a carrier-arm mounted on said shaft, a carrier mounted on said arm, a tension-spring for throwing said arm, and power mechanism for completing the circular swing of said arm to return the same to initial position, as and for the purpose set forth.

3. In a target-trap, a frame, a carrier-arm pivotally mounted thereon, a spring connected to said arm for throwing the same, stop devices for maintaining said arm in position preparatory to being thrown by said spring, and continuously-operating power mechanism for completing the rotary swing of said arm to return the same to initial position preparatory to being released by said stop devices, as and for the purpose set forth.

4. In a target-trap, a pivotally-mounted carrier-arm, a carrier mounted thereon, a spring for throwing said arm about its pivot, means for preventing the rebound or return of said arm in a direction opposed to the direction of swing thereof under the impetus of said spring, and automatic continuously-operating mechanism for completing the swinging movement of said arm to return the same to initial position preparatory to being thrown, as and for the purpose set forth.

5. In a target-trap, a carrier-arm pivotally mounted, a spring connected to said arm for throwing the same, a pawl carried by said arm, and a stationary rack over which said pawl operates, whereby said arm is prevented from rebounding or returning in a direction opposite to the direction of its projecting or swinging movement and constantly-rotating means for resetting said arm, as and for the purpose set forth.

6. In a target-trap, a carrier-arm, a carrier rigidly mounted thereon, means for imparting a swinging throw to said arm, and automatically-detachable power mechanism for

completing the circular swing of said arm to return the same to initial position preparatory to be again thrown, as and for the purpose set forth.

7. In a target-trap, a carrier-arm, a carrier mounted thereon, a spring connected to said arm for throwing the same, detachable stop devices for holding said arm against the action of said spring, in combination with continuously-operating automatically-detachable power devices for positively completing the swing of said arm to return the same, when released, to its initial position preparatory to being tripped, as and for the purpose set forth.

8. In a target-trap, a pivotally-mounted carrier-arm, a carrier mounted thereon, a projecting spring connected to said arm, stop devices for holding said arm against the action of said spring, means for arresting said arm against recoil action when released, and automatically-detachable continuously-operating power mechanism for completing the rotary swing or sweep of said arm to return the same to initial position, as and for the purpose set forth.

9. In a target-trap, a swinging carrier-arm, a carrier mounted thereon, a spring for throwing said arm, stop devices for holding said arm against swinging movement, and continuously-operating power mechanism for positively completing the swing of said arm when released to restore the same to initial position, including detachable clutch devices operating to be disengaged from said arm when the latter attains its initial position, as and for the purpose set forth.

10. In a target-trap, a carrier-frame, a shaft journaled therein, a carrier-arm mounted on said shaft, a crank-arm connected to said shaft, a spring connected to said crank-arm and operating to impart a rotative tension to said shaft, a detachable clutch arranged to engage said crank-arm, and continuously-operating power mechanism for actuating said clutch, as and for the purpose set forth.

11. In a target-trap, a rotatable shaft, a carrier-arm mounted thereon, means for imparting a rotative tension to said shaft, stop devices for locking said shaft against rotative movement under the influence of said tension, whereby when said locking devices are tripped said shaft is rocked to project or swing said arm, in combination with continuously-operating automatically-detachable power-actuated devices for completing the rotary movement of said shaft to return said arm to initial position, as and for the purpose set forth.

12. In a target-trap, a rotatable crank-shaft, a carrier-arm mounted thereon, a crank-arm connected to said shaft, a spring connected to the crank-arm of said shaft and operating to impart a rotative tension to said

shaft to project or swing said carrier-arm, a rotatable clutch having a toe arranged to engage said crank-arm to complete the rotary movement of said shaft, and continuously- 5 operating power mechanism for actuating said clutch, as and for the purpose set forth.

13. In a target-trap, a carrier, a rotatable shaft upon which said carrier is mounted, a spring connected to said shaft, a crank-arm 10 also connected to said shaft, a clutch-block, means for rotating the same, said clutch-block provided with a projecting toe arranged to engage said crank-arm, and means for shifting said clutch-block to move said 15 toe into and out of engaging relation with respect to said crank-arm, as and for the purpose set forth.

14. In a target-trap, a carrier-arm, a spring for projecting the same, and power 20 mechanism for restoring said carrier to initial position preparatory to being projected, including a rotatable cam-block, an extension or toe carried thereby and operating to engage said arm, and means for shifting said 25 cam-block to engage or disengage said toe from said carrier, as and for the purpose set forth.

15. In a target-trap, a carrier-arm, a spring for projecting the same, a power mechanism 30 for restoring said carrier-arm to initial position preparatory to being projected by said spring, including a rotatable clutch-block, a pivoted or yielding extension or toe carried thereby devices intermediate said 35 block and arm and arranged to be engaged by such toe, and means for shifting said clutch-block to project or withdraw said yielding toe into or out of engaging relation with respect to said intermediate devices, as and for 40 the purpose set forth.

16. In a target-trap, a carrier-arm, a spring for projecting the same, a power mechanism for restoring said carrier-arm to initial position preparatory to being projected by 45 said spring, including a rotatable clutch-block, a cam-track arranged adjacent to said rotatable clutch-block, and a stud or projection carried by said block and operating in said cam-track to shift said clutch-block into 50 and out of engaging relation with respect to said carrier-arm, as and for the purpose set forth.

17. In a target-trap, a carrier-arm, a spring for projecting the same, a power mechanism 55 for returning said carrier to initial position, including a rotatable clutch-block arranged to engage said carrier-arm, a stud or projection carried by said block, a cam engaging said stud or projection to shift said 60 clutch-block into and out of engaging relation with respect to said carrier-arm, and means for adjusting said cam, as and for the purpose set forth.

18. In a target-trap, a carrier-arm, means 65 for actuating the same, a power mechanism

for returning the carrier to initial position preparatory to being actuated, including a rotatable shaft, a shiftable clutch-block carried thereby and arranged to engage said carrier-arm, and means for shifting the position 70 of said clutch-block relatively to its actuating-shaft, as and for the purpose set forth.

19. In a target-trap, a carrier-arm, means for actuating the same, a power mechanism for returning said carrier-arm to position 75 preparatory to being actuated, including a rotatable shaft carrying eccentric-pins, a longitudinally-slotted clutch-block, said eccentric-pins operating in said longitudinal slot, whereby said clutch-block is rotated, but 80 permitting a longitudinal movement transversely of said shaft, said clutch-block arranged to engage said carrier-arm, and a cam for shifting said clutch-block upon said pins, as and for the purpose set forth. 85

20. In a target-trap, a carrier-arm, means for operating the same, a power mechanism for returning said carrier-arm to initial position preparatory to being actuated, including a shiftable clutch-block, a yielding toe carried thereby, said toe provided with a curved surface on the rear side thereof, and means for shifting said clutch-block to project or withdraw said yielding toe into and out of engaging relation with respect to the carrier- 90 arm, as and for the purpose set forth. 95

21. In a target-trap, a carrier-arm, a rotatable shaft upon which said arm is mounted, said shaft having a crank, a spring connected to said crank, whereby when said crank 100 passes its dead-center the tension of said spring is exerted to impart a rotary swing to said carrier-arm, power mechanism for positively returning said carrier-arm to initial position, including a clutch, means engaged 105 by said clutch for rotating said shaft, and means for detaching said clutch from engagement with said means when the line of tension of said spring passes the dead-center of said crank, as and for the purpose set forth. 110

22. In a target-trap, a carrier-arm, means for actuating the same and power mechanism for restoring said arm to initial position preparatory to being actuated, including a continuously-rotating shaft, and a clutch mechanism operated by said shaft, devices intermediate said clutch and arm for rocking the latter, and means for automatically detaching said clutch from engaging relation with respect to said devices when the carrier-arm 115 reaches its initial position, whereby said shaft may continue its rotation without affecting said carrier-arm, as and for the purpose set forth. 120

23. In a target-trap, a carrier-arm, a carrier rigidly mounted on said arm, a spring for throwing said arm, stop devices for holding said arm against the action of said throwing-spring, and continuously-operating power mechanism for completing the swinging 125 130

movement of said arm when released by said locking devices to return the same to its initial position, as and for the purpose set forth.

5 24. In a target-trap, a main frame, a standard journaled therein to swing upon a vertical axis, a carrier-frame pivotally mounted upon said standard for swinging movement about a vertical axis, means for adjusting 10 said carrier-frame about its pivot on said standard, a carrier-arm mounted on said carrier-frame, means for actuating said carrier-arm, and means for imparting rotary oscillations to said standard, as and for the purpose 15 set forth.

25. In a target-trap, a main frame, a standard journaled therein to swing about a vertical axis, a carrier-frame mounted on said standard, a carrier mounted on said carrier-frame, means for actuating said carrier, mechanism for automatically restoring said carrier to initial position after the latter is actuated, means for rotarily oscillating said standard, and means for continuously operating 25 said power mechanism, as and for the purpose set forth.

26. In a target-trap, a main drive-shaft, a carrier-frame, a carrier mounted thereon, means for actuating said carrier, automatically-detachable clutch mechanism for restoring said carrier to initial position after being actuated, means operated by said main power-shaft for continuously operating said detachable clutch mechanism, and means 35 also operated by said main power-shaft for imparting rotary oscillations to said carrier-frame, as and for the purpose set forth.

27. In a target-trap, a carrier, a supporting-standard therefor, an arm connected to 40 said standard, a rock-lever engaging said arm, a shaft, means for rotating the same, and connections between said shaft and rock-lever for rocking the latter, whereby rotary oscillations are imparted to said supporting-standard, as and for the purpose set forth.

45 28. In a target-trap, a carrier, a suitably-journaled supporting-standard therefor, an arm connected to said standard, a rock-lever provided with an elongated slot through 50 which said arm operates, a drive-shaft provided with a crank-arm, said crank-arm engaging said rock-lever, whereby rotary oscillations are imparted to said supporting-standard, as and for the purpose set forth.

55 29. In a target-trap, a carrier, means for actuating the same, a frame upon which said carrier is mounted, means for oscillating said frame, a power-driven mechanism for restoring said carrier to initial position including 60 shaft-sections, and feather connections between said shaft-sections to permit of relative longitudinal movement thereof during the oscillations of said carrier-frame, as and for the purpose set forth.

65 30. In a target-trap, a carrier, a support-

ing-frame therefor, and means for imparting rotary oscillations to said frame, in combination with power-driven mechanism for restoring said carrier to initial position when actuated, including a drive-shaft, a shaft 70 mounted in said carrier-frame, shaft-sections respectively connected to said power-shaft and carrier-frame shaft by gimbal-joints, and a sliding ball-bearing joint connection between said shaft-sections, as and for the purpose 75 set forth.

31. In a target-trap, a carrier, a carrier-frame upon which said carrier is mounted, and means for imparting rotary oscillations to said frame, in combination with power 80 mechanism for positively restoring said carrier to initial position when the latter is actuated, a drive-shaft mounted in said carrier-frame, and a power-shaft, shaft-sections respectively connected to said drive and 85 power shafts by gimbal-joints, a sleeve through which said shaft-sections operate, said sleeve and shaft sections being correspondingly grooved, and balls arranged in said grooves, as and for the purpose set forth. 90

32. In a target-trap, a main power-shaft, gears mounted thereon, a vertical shaft driven by one of said gears, a fly-wheel mounted on said vertical shaft, a stud-shaft driven by the other of said gears on said power-shaft, a supplemental shaft driven by said stud-shaft, a carrier, means for operating said carrier, means actuated by said supplemental shaft for imparting rotary oscillations to said carrier, and means actuated by 100 said stud-shaft for positively restoring or returning said carrier to initial position when actuated, as and for the purpose set forth.

33. In a target-trap, a carrier, and means for actuating the same, in combination with 105 a magazine comprising a base-ring having an opening therethrough to permit the passage of a target, arms or levers pivotally mounted upon said base-ring and carrying projections forming supports for the lowermost target 110 contained in the magazine, auxiliary levers carrying clamping-jaws, connections between said arms or levers and said auxiliary levers whereby when the former are spread apart the latter are drawn together, and 115 means for spreading said first-mentioned arms or levers apart, as and for the purpose set forth.

34. In a target-trap, a carrier, and means for actuating the same, in combination with 120 a magazine comprising a base-ring having an opening therethrough to permit the targets to be discharged therefrom, swinging levers pivotally mounted at one end and extending on opposite sides of said opening and carrying inwardly-extending holding projections or ledges, means normally tending to draw the free ends of said levers together, means for separating said levers to withdraw said 125 supporting projections or ledges, and clamp- 130

ing-jaws arranged to be coincidently projected into said magazine when said levers are separated to withdraw said holding projections, as and for the purpose set forth.

35. In a target-trap, a carrier, and means for operating the same, in combination with a magazine comprising a base-ring, levers pivotally mounted at one end upon said base-ring, means for drawing the opposite ends of said levers together, a stud journaled in said base-ring and carrying a cam, said cam operating between the free ends of said levers, supporting-ledges connected to said levers, bell-crank levers pivotally mounted upon said base-ring, auxiliary levers pivotally mounted upon said base-ring and carrying clamping-jaws, one of the arms of said bell-crank levers arranged to engage said auxiliary levers and the other of the arms of said bell-crank levers arranged to engage said first-mentioned levers, and means for actuating said cam, as and for the purpose set forth.

36. In a target-trap, a carrier, and means for operating the same, in combination with a magazine, and means for successively releasing the targets singly therefrom, and a follower arranged to bear upon the stack or pile of targets carried by said magazine and operating to prevent displacement thereof, said follower having a slotted arm and a guide operating in the slot in said arm as and for the purpose set forth.

37. In a target-trap, a carrier, and means for operating the same, in combination with a target-magazine, a follower-plate having slotted arms or extensions, guiding-rods received through the slots in said arms or extensions, said arms or extensions provided with a downturned flange, as and for the purpose set forth.

38. In a target-trap, a support for the target, said support having an unobstructed rear portion to permit the targets to be fed thereon from the rear, and means carried by said support for holding the target thereon.

39. In a target-trap, a support for the target, said support having an unobstructed rear portion to permit targets to be placed thereon from the rear, and contact-points carried by said support to hold the target thereon, one of said contact-points being fixed and the other movable relatively thereto.

40. In a target-trap, a support for the target, said support having an unobstructed rear portion to permit targets to be placed thereon from the rear, and clamping parts for the target, said clamping parts being carried by said support, one of said clamping parts being fixed and the other movable relatively thereto, and means for yieldingly drawing said movable part toward said fixed part.

41. In a target-trap, a support for the target, said support having an unobstructed

rear portion to permit targets to be received thereon from the rear, a curved clamping part carried by said support on one side thereon and arranged to partially embrace a target, and a coöperating clamping-lug mounted on the other side of the support, one of these parts being yieldingly mounted.

42. In a target-trap, a support for the target, said support having an unobstructed rear portion to permit targets to be received thereon from the rear, a curved clamping part fixedly mounted on one side of said support, and a coöperating clamping-lug yieldingly mounted on the other side of the support.

43. In a target-trap, a throwing-arm and means for operating the same, in combination with a support for the target rigidly mounted on the free end of said arm, said support having an unobstructed rear portion to permit targets to be placed thereon from the rear, and clamping parts carried at the front portion of said support to clamp or hold the target therebetween, one of said clamping parts being fixed and the other yieldingly mounted.

44. In a target-trap, a support having clamping parts at the forward portion thereof to receive the target therebetween, said support having an unobstructed rear portion to permit the targets to be inserted between said clamping parts from the rear.

45. A carrier for target-traps comprising a supporting-base having an unobstructed rear portion providing a rear feed-opening, and fixed and yielding contact-points for holding a target on said base.

46. A carrier for target-traps comprising a supporting-base having an unobstructed rear portion providing a rear feed-opening, and fixed and yielding contact-points for holding a target on said base, consisting of an arm and a post coöperating with said arm.

47. A carrier for target-traps, comprising a supporting-base having a rear pivoted head, an unobstructed rear portion providing a rear feed-opening, and fixed and yielding contact-points for holding the target on said base.

48. A carrier for target-traps comprising a bottom support having an attaching-head and an unobstructed upper surface, an arm-attaching projection near the rear portion of said base, an arm carried by said projection and a post coöperating with said arm to hold the target; the arm-supporting projection being separated from the post to leave an unobstructed rear feed-opening on the bottom support to permit the target to be inserted from the rear, and the post and arm being made relatively yielding to permit the escape of the target.

49. The combination of a throwing-arm, a carrier, secured to the outer end thereof, having a base for supporting a target, and a fixed and yielding contact device projecting up-

ward from said base near the outer end thereof, said carrier being devoid of all such obstructions above its rear surface as will prevent the movement, upon the base, from the rear thereof into contact with said contact devices, of a target of large enough diameter to be properly restrained by said contact devices during the discharging movement of the throwing-arm.

50. A target-trap comprising a frame having a ratchet-faced portion, a rotatably-mounted throwing-arm supported by said frame, means for rotating said throwing-arm in a complete circle, and a catch carried by said throwing-arm for engagement with said ratchet-faced portion to prevent return movement of the throwing-arm after it has passed its throwing position.

51. A target-trap comprising a frame having a ratchet-faced extension, a rotatably-mounted throwing-arm, adapted to move in a complete circle, means for operating said throwing-arm, and a catch carried by said

throwing-arm for engagement with said ratchet-faced extension after the throwing-arm has passed its throwing position.

52. A target-trap comprising a frame, a throwing-arm mounted upon said frame and adapted to move in a complete circle, a ratchet-faced semicircular extension connected with the frame, a catch carried by said throwing-arm for engagement with said extension after the throwing-arm has passed its throwing position, springing means having connection with said arm, and a trigger for maintaining the arm in a fixed position while the springing means is being placed in active condition.

In witness whereof I have hereunto set my hand, this 3d day of March, 1902, in the presence of the subscribing witnesses.

LOUIE A. SHERMAN.
